Albert E. Maspons
BY Cornelius L. O'Brien
his ATTORNEY.

UNITED STATES PATENT OFFICE.

ALBERT E. MASPONS, OF PHILADELPHIA, PENNSYLVANIA.

STRUCTURE FOR OPERATING UPON CIGAR WRAPPINGS.

1,417,938.

Specification of Letters Patent. Patented May 30, 1922.

Application filed February 11, 1920. Serial No. 357,986.

To all whom it may concern:

Be it known that I, ALBERT E. MASPONS, a citizen of the United States, residing in the city and county of Philadelphia, State 5 of Pennsylvania, have invented new and useful Improvements in Structures for Operating Upon Cigar Wrappings, of which the following is a specification.

My invention relates to wrapping cigars 10 with tin foil or equivalent, and relates more particularly to operations performed upon the foil at the ends of the cigar where it attains considerable thickness by over-folding, crumpling or the like incident to folding 15 or twisting the foil to complete the envelopment or enclosure of the cigar therein.

My invention resides in apparatus for operating upon the foil at the cigar ends for removing excess thereof, bringing the foil 20 to a predetermined or suitable shape preferably conforming with a cigar, and smoothing or molding the foil at the cigar ends.

For an illustration of structures comprehended within my invention, reference is to 25 be had to the accompanying drawings, in which:

Figs. 1 and 2 are sectional and end views, respectively, of structure for operating upon the foil upon the head end of a cigar.

30 Figs. 3 and 4 are sectional and end views, respectively, of similar structure for operating upon the tuck end.

Figs. 5 and 6 are sectional and end views, respectively, of modified structure for operating upon the head end of a cigar.

35 Figs. 7 and 8 are sectional and end views, respectively, of a modified structure for operating upon the tuck end of a cigar.

Fig. 9 is a sectional view of structure 40 similar to Fig. 1 showing a cigar and its foil wrapping receiving treatment.

Referring to Fig. 9, C is a cigar which has been rolled in a sheet of tin foil F, the latter being creased and folded and worked 45 down over the head or point of the cigar and so becoming more or less crumpled and forming a considerable mass of foil in excess of that suitable or desired for the finished product. The extreme end of the foil 50 is operated upon by the cutter edges c, which are rotated with respect to the foil and cigar, so shaving or cutting off small fragments of foil and reducing the excess until there is practically remaining only sufficient foil 55 closely to conform to the shape of the cigar head.

The cutter edges are formed in a thimble or shell T conforming substantially with the head of the cigar, the smooth portion s of the thimble to the right of the cutter 60 edges c smoothing down or molding the foil of a cigar head which is not operated upon by the cutters.

The cigar and its foil wrapping are preferably held stationary while the thimble T 65 rotates, either continuously in one direction or by backward and forward rotary oscillations. It will be understood, however, that the thimble T may be stationary and the cigar and its wrapping rotated or oscillated. 70

Referring to Figs. 1 and 2, the thimble T is shown as integral with the rim or flange f, though they may be separate and suitably attached to each other. The cutting edges c may be formed in any suitable way. In 75 the example illustrated they are formed at the point of the thimble by crossed slots whose edges are sufficiently sharp for cutting or shaving the tin foil, the removed foil finding egress through the slots or perforations.

The thimble is supported by the flange f, which is held by a cage comprising the fingers b upstanding from the base or disk a. Screws d are preferably employed for holding 85 the thimble to the fingers b, the screws extending through the fingers and threaded into the flange or rim f of the thimble.

The structure may be rotated by any suitable means, as for example, a shaft e threaded into the disk a, the axis of rotation of the shaft e being co-incident with the axis of the thimble T.

In Figs. 3 and 4 the structure is similar to that shown in Figs. 1 and 2, except that the thimble is of different shape, frusto-conical, for operating upon the foil upon the tuck or opposite end of a cigar from that operated upon in the structure shown in Figs. 1 and 2. In this case the cutting slots are in the 100 flat portion g of the thimble T. In consequence the foil on the tuck end only of the cigar is operated upon, though the inner surface of the conical portion of the thimble T may, if desired, be employed to smooth or 105 mold the foil adjacent the tuck end.

In Figs. 5 and 6 the structure is similar to that shown in Fig. 1, except cutting edges are procured by a series of holes i suitable in number and suitably positioned. The 110 general effect and mode of operation, however, is the same.

In Figs. 7 and 8 the structure is similar to that shown in Figs. 3 and 4, except the cutting edges are, as in Figs. 5 and 6, the edges of holes *i* in the base portion *g* of the 5 thimble *T*.

According to my invention, the cigar is rolled up in a sheet of tin foil or equivalent, the foil being pressed and formed around the cigar and at the ends twisted and folded 10 or crumpled to form close contact therewith, and then the head and tuck ends are operated upon as described to remove excess foil and mold and work it and form it into position in close contact with the cigar itself, 15 hiding or filling imperfections, if any, in the cigar itself, and so producing a finished product which is neat and pleasing in appearance and yet effectively enveloping or enclosing the cigar even at its ends in the 20 foil wrapping.

While I have herein referred to a cutting edge as formed at or by the perforation in the thimble, it will be understood that the edge of the perforation, while preferably 25 sharp and cutter-like, may nevertheless be more or less blunt or rounded, in which case also by friction or other action small particles of foil will be abraded or removed and effect the end sought.

30 What I claim is:

1. Structure for dressing the foil upon the end of a foil-wrapped cigar comprising a thimble rotatable with respect to the cigar and conforming substantially to the shape 35 of the cigar end, and foil-removing means in said thimble, said thimble having a foil-discharging aperture.

2. Structure for dressing the foil upon the end of a foil-wrapped cigar comprising a recessed member rotatable with respect to the cigar and adapted to receive the foil-covered 40 cigar end and having a perforation forming a cutting edge.

3. Structure for dressing the foil upon the 45 end of a foil-wrapped cigar comprising a recessed member adapted to receive the foil-covered cigar end and having a perforation forming a cutting edge, and means for rotating said member,

4. Structure for dressing the foil upon the 50 end of a foil-wrapped cigar comprising a recessed member adapted to receive the foil-covered cigar end, and foil removing means in said thimble, said thimble having a foil-discharging perforation, and rotatable 55 means for supporting said member to allow free egress of removed foil.

5. Structure for dressing the foil upon the end of a foil-wrapped cigar comprising a thimble having perforations, a flange on 60 said thimble, fingers supporting said flange, a base supporting said fingers, and means for rotating said base.

6. Structure for dressing the foil upon the end of a foil-wrapped cigar comprising a 65 cage, means for rotating said cage, a thimble whose end is disposed within said cage and free of the sides thereof, perforations in the free end of said thimble, and means supporting said thimble at its other end on said cage.

7. Structure for dressing the foil upon the end of a foil-wrapped cigar comprising a 75 member having a recess adapted to receive the foil-covered cigar end, the wall of said recess comprising a surface of revolution for smoothing the foil, and means for rotating said member with respect to the cigar.

8. Structure for working the foil upon the end of a foil-wrapped cigar comprising a 80 member having a recess adapted to receive the foil-covered cigar end, said member having an aperture adjacent the bottom of said recess forming a cutting edge substantially flush with the inner surface of said recess, 85 and means for causing relative rotation between said member and the foil.

9. Structure for dressing the foil upon a foil-wrapped cigar comprising a member rotatable with respect to the cigar and having 90 a recess adapted to receive the foil-wrapped cigar, said recess having a wall for smoothing the foil, and said member having an aperture forming a foil-removing edge.

In testimony whereof I have hereunto affixed my signature this 10th day of February, 1920.

ALBERT E. MASPONS.
